THERMOSTATIC CONTROL UNIT

Siegfried E. Manecke, John W. Stearley, and James L. Shaw, Indiana, Pa., assignors to Robertshaw Controls Company, Richmond, Va.

Filed Aug. 5, 1975, Ser. No. 602,078

Term of patent 14 years

Int. Cl. D10—04

U.S. Cl. D10—50

FIG. 1

FIG. 2

FIG. 3

FIG. 4

FIG. 6

FIG. 5

FIG. 1 is a top left front perspective view of a thermostatic control unit showing our new design;

FIG. 2 is a front elevational view thereof;

FIG. 3 is a right side elevational view thereof;

FIG. 4 is a top plan view thereof;

FIG. 5 is a bottom plan view thereof; and

FIG. 6 is a rear elevational view thereof.

We claim:

The ornamental design for a thermostatic control unit, substantially as shown and described.
